UNITED STATES PATENT OFFICE.

GEORGE R. WIXON, OF FAIRHAVEN, MASSACHUSETTS.

DESIGN FOR A HANDLE FOR SWORDS OR THE LIKE.

SPECIFICATION forming part of Design No. 22,008, dated November 22, 1892.

Application filed October 27, 1892. Serial No. 450,185. Term of patent 14 years.

To all whom it may concern:

Be it known that I, GEORGE R. WIXON, a citizen of the United States, residing at Fairhaven, in the county of Bristol and State of Massachusetts, have invented and produced a new and original Design for Handles for Swords, Whips, Canes, or the Like; and I do hereby declare the following to be a full, clear, and exact description of the same.

10 This invention or production relates to designs for the handles of swords or the like, as will be more fully understood on reference to the accompanying drawings, in which—

15 Figure 1 is a perspective view of a handle, showing my design; and Fig. 2 is a view of the design or handle, looking to the right of Fig. 1.

20 The leading feature of my design consists in a handle having a straight portion, the outer surface of which presents a number of closely-fitting ribs and a portion or guard constituted of three or more parts curving outwardly from said straight portion and uniting therewith at each end, the said curved portions presenting a similarly-ribbed surface and united by a series of rings, the same having the appearance of being interwoven with said curved portions. The lower extremity of

one of the curved portions terminates in a tight coil.

30 In the drawings, A represents the straight portion of the handle, having a rounded or circular top *a*, the surfaces of both being ribbed, as shown by the letter *b*.

35 B, C, and D represent the curved portions of the handle leading out from the part A and similarly ribbed, as shown at *c*. These portions are connected by the rings *d*, as shown, and the lower extremity of the portion D terminates in a coil *e*. The said portions have the appearance of being united at their lower ends to the part A by means of a wrapping *f*.

What I claim is—

40 The design for a handle for swords and the like, herein shown and described, the same comprising the straight portion A and the curved portions B, C, and D, each presenting a ribbed surface, the said portions B, C, and D being connected by the rings *d* and the portion D terminating in the coil *e*, as set forth.

45 In testimony whereof I affix my signature in presence of two witnesses.

GEORGE R. WIXON.
